EXPANDING DIE FOR SHEET METAL PRESSES

George G. Greene, Warren, Pa.; Glenn George Greene, Jr., executor of said George G. Greene, deceased, assignor to G. G. Greene Manufacturing Corporation, Warren, Pa., a corporation of Pennsylvania

Application June 4, 1946; Serial No. 674,358

6 Claims. (Cl. 113—48)

1

This invention relates to mechanisms for making bases for radio tubes, and similar articles, and it relates more particularly to the manufacture of that type of radio or vacuum tube base which comprises a metal cup to be fixed to the glass or envelope of the tube, and having a centrally disposed depending stem. More specifically, the invention relates to means for forming a longitudinally disposed key on the depending stem to ensure proper position of the tube when assembled in its socket, and to form a locating boss on the outer wall of the cup portion adapted to be felt by the fingers grasping the tube for insertion in the socket, and thereby readily locating the key.

Vacuum or radio tube bases of the character mentioned are made on a transfer die press, and the process requires a plurality of successive operations, usually eleven, the work being automatically passed from each station or die to the next in order, so that the die press completes the several operations with each stroke. However, with these die presses, operating in successive steps as mentioned, it has heretofore been considered impossible to form the locating boss in the side of the base as the operative stroke of the press plunger at all stations is in one direction, whereas a stroke to form said boss must be in a direction transverse to said stroke. Furthermore, the space available for such an operation in a die press of this character is extremely limited, and it has been deemed impracticable to equip the press with means for performing this additional operation.

The object of this invention is to provide in a press of the character mentioned, mechanism for forming a locating boss on the side of the base in unison with the several steps in making the base.

A further object of the invention is to provide means for forming the locating boss, as mentioned, which can be accommodated in the limited amount of space available in the press.

A further object of the invention is to provide a single die by means of which a locating boss may be formed on the side of the base, and a key formed on the depending stem, simultaneously therewith.

Other objects will appear hereinafter.

With these objects in view the invention consists generally in a reciprocating head having a portion adapted to enter a preformed tube base, and means within said head and actuated in a direction transverse to the path of reciprocation

2

of said head, for forming a boss on the side wall of said base.

The invention further consists in providing a reciprocating head with cooperable die members arranged for transverse movement in the end of said head, and means, actuated by the reciprocation of said head to operate said die members to form a boss on the side wall of tube base.

10 The invention further consists in a device as above stated in which the means for operating one of the die members is equipped with means for forming a key on the depending stem.

The invention further consists in various details of construction and combinations and arrangements of parts, all as will be hereinafter described and particularly pointed out in the claims.

The invention will be more readily understood by reference to the accompanying drawings forming a part of this specification, and in which:

Fig. 1 is a vertical sectional view of a die press embodying this invention, showing the head in raised position.

Fig. 2 is a similar view, showing the head at the end of its operative stroke.

Fig. 3 is a bottom plan view of the reciprocating head.

Fig. 4 is a section on the line 4—4 of Fig. 1.

Fig. 5 is a transverse section on the line 5—5 of Fig. 2.

Fig. 6 is a side elevation on an enlarged scale of one of the completed tube bases.

Fig. 7 is a bottom plan view of the completed base.

Fig. 8 is a detail section of the lower portion of the die, similar to Fig. 1 but upon a much enlarged scale, and

Fig. 9 is a view similar to Fig. 8, the parts being illustrated with the head at the lower end of its operative stroke.

Similar parts are designated by the same reference characters in the several figures.

As hereinbefore stated, the object of this invention is to provide means for forming a locating boss on the side wall of a preformed radio tube base, and a key on the depending stem thereof. Such a tube base is made of brass or other suitable metal and a completed base of this character is illustrated in Figs. 6 and 7 of the drawings. As shown therein, the base 20 comprises a cylindrical side wall 21, a bottom wall 22, and a central depending stem 23. The upper edge of the wall 21 is slightly flared as at 24 to conform to the glass or other envelope of the tube

when assembled. The bottom 22 is slightly raised forming an annular bead or seat 25, and a plurality of apertures 26 are provided in the bottom 22 for the several terminal contact pins of the tube. A locating boss 27 is provided on the side wall 21, and a key 28 is formed on the stem 23 to assure proper positioning of the tube with the various contact pins thereof in engagement with the respective contacts in the socket with which it is designed to be used.

The device embodying the present invention comprises a supporting die member for a pre-formed tube base, such as above described, without the boss 27 and key 28, and a reciprocatory member including a head having a portion thereof adapted to enter the tube base, transversely movable die members for forming the boss 27 on the wall of the base, and means actuated by the reciprocation of said head for operating said die members. The invention also includes means for forming the key 28 on the stem 23.

Referring to the drawings, 29 indicates the support or lower die member for the preformed tube base, to which said base is transferred from the preceding die or station of the press. The transfer mechanism employed may be of known form and is therefore not illustrated or described herein. The upper face of the support 29 is shaped to conform to the bottom of the tube base, and is provided with a bore 30 to receive the depending stem 23 thereof. The side wall of the bore 30 is formed with a longitudinally disposed groove 31, for a purpose hereinafter described.

Supported above the lower die member 29, and in axial alignment with the bore 30 thereof, is a vertically reciprocatory die member including a head 32 and a supporting plunger 33 upon which the head is telescopically mounted. The plunger 33 comprises a shank 34 by which the device is attached to the usual vertically reciprocatory member of the press (not shown), a threaded portion 35 for lock nuts 36, a reduced stem portion 37 and an enlarged lower end or head 38. The enlarged end 38 is slidably mounted within a bore 39 in the head, and is retained therein by arcuate plates 40 surrounding the stem 37 and secured to the upper end of the head, as by screws 41, with a space or kerf 42 between the adjacent portions of the plates. A spring 43 is interposed between the lower nut 36 and the plates 40 to normally hold the head 32 extended or in lowermost position relatively to the plunger 33.

The head 32 includes a depending extension comprising a centrally disposed portion 44 of reduced diameter, and a portion 45 extending radially therefrom. See Fig. 3. The lower end of the cylindrical portion 44 is adapted to enter the tube base 20 when the head is in lowered position, and is sufficiently smaller in diameter than the inner diameter of the tube base to freely enter and leave said base without binding. An arcuate slot or recess 46 is provided between the portions 44 and 45 to receive the adjacent portion of the wall 21 of the tube base, and the lower inner edge of the portion 45 is beveled as at 47.

Attached to the lower end of the plunger 33, and extending downward through a centrally disposed bore 48 in the head 32, is a punch 49, the lower end 50 of which is shaped to fit within the stem 23 of the tube base when the plunger reaches its lowermost position, as illustrated in Figs. 2 and 9. When the plunger 33 is raised, the punch 49 is retracted within the head 32 before the head starts its upward movement, the spring 43 maintaining said head in depressed position until the

enlarged end 38 of the plunger engages the plates 40 and raises the head.

Extending diametrically through the end of the portion 44 which enters the base 20, and at right angles to the path of reciprocation of the head 32, is a bore 51; and slidably mounted in the portions of said bore, between the vertical bore 48 and the recess 46, is a die member or plunger 52. The end of the bore 51 adjacent the recess 46 is reduced in diameter forming an annular shoulder 53, and the plunger 52 is provided with an extension 54 of reduced diameter fitting within said reduced portion of the bore.

The ends of the plunger 52 are preferably formed spherically, as at 55 and 56 and the proportions are such that when one of said spherical ends is entirely within the bore the other end projects outwardly into the bore 48 or recess 46 as the case may be. The spherical ends 55 and 56 constitute cams, so that as the portion 44 is lowered into the base 20, the upper edge of the wall 21 of the base will engage the cam end 55 and move the plunger 52 inwardly with the end 56 projecting into the bore 48, where, by further downward movement of the punch 49, a cam shoulder 57 on the punch will engage said end and force the plunger in the opposite direction as will be more fully described hereinafter.

The portion 45 of the head is provided with a bore 58 in alignment with the bore 51 and preferably of the same diameter as the reduced portion thereof. Slidably mounted in the bore 58 is a die member 59 having a concave inner end 60 and a convex outer end 61. The die member 59 is provided with a longitudinally disposed, depending flange or fin 62 having a beveled inner end forming a cam 63 to be engaged by the flared edge 24 of the base to force the said member outwardly as the head 32 is lowered, to prevent the die member from interfering with the free or unobstructed entry of the wall 21 of the tube base into the recess 46. Intersecting the bore 58 is a vertically extending bore 64 in which is mounted a reciprocatable cam pin 65 having a recess 66 on its inner face, said recess terminating at its lower end with an inclined cam face 67.

When the head 32 moves downwardly, the cam pin 65 engages means to arrest further movement of the pin. Such arresting means may be provided by a suitable abutment as indicated at 68. With further downward movement of the head, the flared edge 24 of the tube base engages the cam 63 and forces the die member 59 outwardly, after which the convex end face 61 of the die member 59 rides on the cam 67 and pushes the member 59 inwardly until the edge of the concave end 60 engages the outer face of the wall 21 of the tube base. By this time the lower end of the portion 44 is within the said base and resting on the bottom wall 22. This arrests the downward movement of the head 32, but the stem 33 continues to move downwardly and the punch 49 enters the stem 23 of the tube base. As the cam 57 passes the cam face 56 of the plunger 52, it forces said plunger outwardly, so that the convex end 55 cooperates with the convex end 60 of the die member 59 to form the boss 27.

As the punch end 50 enters the stem 23 of the tube base, a longitudinal rib or fin 69 forces the adjacent portion of the wall of the stem into the groove 31 to form the key 28. Preferably, the rib or fin 69 is in the same radial plane with the axes of the die member 59 and plunger 52 so that the boss 27 and key 28 will be similarly positioned on the finished base 20.

As the head rises, a punch 70, or other suitable means engages the upper end of the pin 65 to depress the same in order to permit retraction of the die member 59.

While the present preferred construction for carrying my invention into effect has been illustrated and described, it is to be understood that equivalent constructions are contemplated and will be included within the scope of the claims.

I claim:

1. In mechanism of the class described, a support for a preformed tube base provided with a depending stem comprising a bore to receive the depending stem thereof, said bore having a longitudinal groove in its side wall, in combination with a reciprocable plunger, a head telescopically mounted on said plunger, a spring interposed between said head and said plunger, inner and outer depending portions on said head, the inner portion adapted to enter the tube base and the outer portion positioned radially outwardly from the inner portion, an inner die in the inner depending portion, a cooperating outer die in the outer depending portion and positioned radially outwardly of the inner die, means actuated by the downward movement of said head to move the outer die into engagement with the outer face of the wall of the tube base, a punch on said plunger having a lower end shaped to conform to and adapted to enter said stem on the tube base, a cam on said punch adapted to force the inner die into engagement with the inner face of the tube base wall, and a longitudinally disposed rib on said lower end of said punch to force a portion of the wall of said stem into the groove in said support to form a key on said stem.

2. Mechanism as set forth in claim 1 in which said rib on the punch is in radial alignment with the inner and outer dies.

3. In a mechanism of the class described, a support for a preformed tube base provided with a bore to receive the depending stem thereof, in combination with a reciprocable head having an inner depending portion adapted to enter a tube base on said support and an outer depending portion positioned radially outwardly therefrom, cooperating inner and outer die members mounted in said depending portions respectively for movement toward and from one another transversely of the direction of reciprocation of the head, the outer die member being positioned radially outwardly from the inner die member, means on the outer die member in said outer depending portion engageable with the edge of the tube base to retract said outer die member as said edge enters the space between said depending portions, means actuated by the movement of said head toward said support for moving said die members toward one another in a direction transversely of the direction of reciprocation of the head to form a boss on said tube base, and means associated with said head for forming a key on said stem.

4. Mechanism for forming a boss on a side wall of a preformed cup-shaped tube base and forming a key on a depending stem on the base, com-

prising a support for the tube base having a bore to receive the stem on the tube base and having a groove in a side of the bore and extending axially thereof, a reciprocatory plunger, a head carried by and having a limited relative movement axially of the plunger and having a central portion adapted to enter a tube base on the support and an outer portion positioned radially outwardly from said central portion and adapted to assume a position at the outer side of the side wall of the tube base, inner and outer die members mounted respectively in said central and outer portions of the head in alinement radially of the central portion for movement toward and from one another in a direction transversely of the direction of reciprocation of the head, a punch connected to the plunger and having a portion thereof shaped to enter the stem of a tube base on the support and having a rib on a side thereof in radial alinement with the die members and the axially extending groove in the bore of the support, said rib portion of the punch being operative to force a portion of the stem on the tube base into said groove and thereby form a key on a side of the stem on the tube base, a cam having means for operating it by relative movement between the support and head while the central portion of the head enters the tube base to force the outer die member inwardly against the side wall of the tube base, and a cam on the punch engageable with the inner die member and operative to force the inner die member outwardly against the side wall of the tube base to form a boss on said wall in radial alinement with the key formed on the stem of the tube base.

5. Mechanism as defined in claim 4, including a cam on the outer die member engageable with the upper peripheral edge of the side wall of the tube base while the central portion of the head enters the tube base for retracting the outer die member into a position to clear the side wall of the tube base.

6. Mechanism as defined in claim 4, wherein the outer end of the inner die member is provided with a spherical surface which is engageable with the upper peripheral edge of the side wall of the tube base while the central portion of the head enters the tube base to retract the inner die member into a position to clear the side wall of the tube base.
